ATTORNEY.

UNITED STATES PATENT OFFICE.

LEWIS GIBBS, OF CANTON, OHIO, ASSIGNOR TO THE BUCHER & GIBBS PLOW COMPANY, OF SAME PLACE.

GANG-PLOW.

SPECIFICATION forming part of Letters Patent No. 447,724, dated March 3, 1891.

Application filed June 25, 1890. Serial No. 356,618. (No model.)

To all whom it may concern:

Be it known that I, LEWIS GIBBS, a citizen of the United States, and a resident of Canton, county of Stark, State of Ohio, have invented a new and useful Improvement in Gang-Plows, of which the following is a full, clear, and exact description, reference being had to the accompanying drawings, making part of this specification.

10 My invention relates to improvements in gang-plows; and it consists in providing means for guiding or changing the line of draft and for holding the plows to the desired line.

With these ends in view my invention consists in certain features of construction and combination of parts, as will be hereinafter described, and pointed out in the claims.

Figure 1 of the accompanying drawings is a view in perspective from right front illustrating my invention. Fig. 2 is a similar view from left rear. Fig. 3 is a similar view of the front of the beam, showing the manner of connecting the guiding-tongue and clevis. Fig. 4 is a side elevation showing the manner 25 of connecting the switch-wheel to the plow-frame. Fig. 5 is a perspective of a locking-hub by which the furrow-wheel yoke is locked to the guiding-lever.

As my invention is applicable to gang-plows now in use, and particularly so to the gang-plow shown and described in Letters Patent granted to me bearing date the 30th day of April, and No. 402,155, I will proceed with the description, referring to other parts 35 of the plow only as conjunctional thereto.

Calling attention to Fig. 1, A and A' represent the plow-beams, which are parallel, as shown; B, the plows; C, the supporting-wheels, and D and D' the cranked and divided axles.

To the front end of the beams A A' there is secured a clevis composed of the jaws a, having flanged edges a' to form a socket a² to embrace the front end of the beams, and a series of perforations a³, placed in vertical order at the front portion of the jaw, in which is placed a cross-bar a⁴, that may be adjusted vertically in the said perforations, by which the line of draft may be adjusted vertically.

50 On the bar a⁴ and between the jaws is placed a sliding portion of the clevis consisting of a

sleeve portion a⁵, having a rearwardly-projected loop a⁶, a stop a⁷, and in front of said sleeve and integral therewith a laterally-projected portion a⁸, having a series of perforations a⁹, in which the draft chain or link a¹⁰ may be secured in desired lateral adjustment. A bar b connects the top portion of the jaws a and serves as a support for the sliding tongue-support G, said support having a sleeve portion b² to slide on the bar b and a socket b³ to receive the tongue. A plate b⁴, having a series of perforations b⁵, to which the front end of the shifting lever H is pivotally secured, is provided with arms that embrace the bar b at each end of the sleeve b², which serve to move the sleeve on the bar as the lever H is moved. On the front end of said lever are provided jaws b⁶, which are connected by a vertical rod b⁷, which passes through the loop a⁶ and engages the stop a⁷. The rear end portion of the tongue is secured in the socket b³ by the bolt b⁸.

The lever H is pivotally secured to an arm b⁹, projected from a sleeve b¹⁰, secured between 75 the beams by a through-bolt, and is secured in desired lateral adjustment by the engagement of a spring-actuated bolt of the usual form with the teeth of the rack d.

To the beam A' is secured a forwardly-curved standard K, having secured thereto in a sliding relation a correspondingly-curved rack L, having elongated apertures d' and rearwardly-projected teeth d². Said rack is held in position by bolts d³, passed through 85 the apertures d', on which the rack may slide. A coil-spring d⁴ is provided, as shown, having one of its ends secured to the end portion of the standard K, the other to the upper end of the rack L, the energy of which is exerted 90 against the rack.

On the axle D is secured a sleeve d⁵, having on one of its ends a segmental rack d⁶. The end of the axle D' is passed into the sleeve d⁵ and is held in engagement therewith by 95 the lock-lever d⁷. To the segment d⁶ is secured a hand-lever M, having a spring-actuated locking-bolt of the usual form to engage the teeth d² of the rack L. The levers H and M are extended rearwardly to a point within 100 easy reach of the operator.

In operation the hand-lever M is moved lat-

erally to move the tongue J and the sliding portion d^5 of the clevis laterally on the bars a^4 and b to give the plows more or less land, and may be secured in desired lateral adjustment by the locking-bolt engaging the rack d ; and to adjust the line of draft vertically the bar a^4 may be shifted to the desired apertures a^3 in the jaws a . To raise or depress the front ends of the beams A A', the lever 10 M is depressed or raised and secured in desired adjustment by the locking-bolt engaging the teeth d^2 of the rack L. The object of the spring is to cushion the plow and protect it from breakage by either the plows or the 15 wheels coming against an obstruction, as in the event of the plow catching upon a root or rock the spring will yield to the blow or pressure, the lever M and the sliding segment L will move up and about the central portion of the axles D and D' to allow the front end of the beams to drop or the plows to rise, as the case may be, and in case the wheels C strike an obstruction the yielding of the 20 spring will allow the wheel to yield or rise 25 and pass over without doing violence to the wheel or materially interfering with the operation of the plows. To further control the movement of the plows to hold them up to a desired line, particularly on the side of 30 a hill, where the tendency is to slide or move away from the land, a furrow-wheel N, having a swiveled connection with the supporting-frame, is provided, having its axis fixed in the free end of the yoke h, said yoke secured at its front end in vertical adjustment 35 to the shaft h', journaled or swiveled in the frame P by the set-screw h³, said shaft having at its upper and lower end portions removable collars h⁴, by which it is held in adjustment in the supporting-frame. At the 40 upper end of the sleeve portion h⁵ of the yoke h is provided an upwardly-projected lug h⁶. On the shaft h' is placed a hub portion h⁶, having recesses h⁷ and h⁸, as shown in Fig. 5. 45 Said hub is held against the sleeve h⁵ by the downwardly-exerted energy of the coil-spring h⁹, placed about the shaft h', the upper end of the spring to take under the collar h⁴. A foot-lever Q is provided, having at its rear 50 end prongs k, the ends of which are rounded and adapted to take in the sockets h⁷ in the hub h⁶, the lever resting on and pivoting over the arm k', secured to the frame P. At the front portion of the lever is provided a foot-piece and a stud or pin h² to engage the teeth h³, provided on the front edge 55 of the foot-rest R. In operation the sleeve h⁵ of the wheel-yoke h is locked to the hub h⁶ by the lug h⁶ entering the socket h⁸. The lever 60 Q, engaging the rack h³ on the foot-rest R, will hold the wheel N to a desired line, which may be varied by moving the front end of the foot-

lever laterally and engaging it with the rack at desired adjustment, giving the desired lead to the wheel, by which the rear portion of the 65 plows may be inclined either to the right or left, as the case may be, and at the turning-point the lever Q may be passed down to raise the hub h⁶ above the lug h⁶ to allow the wheel N to turn freely about its swiveled connection with the frame P to allow the plows to be more easily turned at the point of turning. 70

Having thus fully described the nature and object of my invention, what I claim as new, and desire to secure by Letters Patent, is— 75

1. The combination, with the plow and the cranked axle-shaft, of the curved standard, a rack to slide on said standard, a spring to resist the movement of said rack, and a hand-lever to engage the rack, substantially as described, and for the purpose set forth. 80

2. The combination, with the plows and the beams A and A', the cranked axle D and D', of a yielding rack and a hand-lever to engage said rack, substantially as described, and for 85 the purpose set forth.

3. The combination, with the plows and the beams A and A', of a clevis to engage the front ends of said beams, consisting of the jaws a, a bar a⁴, connecting said jaws, a sleeve 90 a⁵ to slide on said bar, said sleeve having a loop a⁶ and a perforated plate portion a⁸, and a hand-lever by which said sleeve may be moved laterally and secured in desired adjustment, substantially as described, and for 95 the purpose set forth.

4. The combination, with the plows and the beams A and A', of the clevis-jaws secured to said beams, a bar b² to connect said jaws, a tongue-support having a sleeve portion b³ to 100 slide on said bar, a link portion b⁴, and a hand-lever H, by which said sleeve and tongue may be moved laterally on said bar simultaneously with the clevis, substantially as described, and for the purpose set forth. 105

5. The combination, with a plow, of a rear furrow-wheel swiveled thereto, a wheel-supporting yoke having lugs h⁶ and a vertical shaft or spindle h', a hub h⁶ about said shaft, having recesses to engage said lugs, a coil-spring to hold said lugs and recesses in engagement, and a foot-lever having one of its ends to engage said lug, the other to engage a rack by which said wheel may be held in desired adjustment and released to turn freely 110 about its pivotal connection with the plow, substantially as described, and for the purpose set forth. 115

In testimony whereof I have hereunto set my hand this 23d day of June, A. D. 1890.

LEWIS GIBBS.
